ABSTRACT

A microphone a shell assembly, a sound pickup assembly, a control assembly and a light-emitting assembly. The shell assembly includes an outer shell with a first accommodating chamber, wherein the outer shell has light transmittance. The sound pickup assembly includes a microphone head for sound pickup, wherein the microphone head is arranged on the shell assembly. The control assembly includes a first circuit board, wherein the first circuit board is arranged in the first accommodating chamber, and is electrically connected to the microphone head. The light-emitting assembly includes a light-emitting unit, wherein the light-emitting unit is arranged in the first accommodating chamber and is electrically connected to the first circuit board. The light-emitting unit is configured to allow emitted light to pass through the outer shell.

CROSS-REFERENCE TO RELATED APPLICATIONS

The application claims priority of Chinese patent application CN202323133044.5, filed on Nov. 20, 2023, which is incorporated herein by reference in its entireties.

TECHNICAL FIELD

The present disclosure relates to the technical field of microphones, and in particular, to a luminous microphone.

BACKGROUND

The application for microphones can be traced back to the late 19th century. Scientists were dedicated to finding better ways to pick up sounds to improve applications such as telephones. With the emergence of ribbon microphones in the 1920s, there are more and more styles of microphones over time, and their functions have become more diverse.

With the development of the microphone technology, some existing microphones not only have a sound pickup function, but also have a function of creating atmospheres. These microphones are usually provided with several light-emitting diode (LED) lamps at their microphone heads, so that LEDs of the LED lamps emit light towards a mesh enclosure or a sponge cover to create an atmosphere. This setting allows the light to be transmitted outward through the mesh enclosure or sponge cover, thereby creating a dispersed lighting effect.

SUMMARY

In a first aspect, the present application provides a microphone. The microphone a shell assembly, a sound pickup assembly, a control assembly and a light-emitting assembly.

The shell assembly includes an outer shell with a first accommodating chamber, wherein the outer shell has light transmittance;

The sound pickup assembly includes a microphone head for sound pickup, wherein the microphone head is arranged on the shell assembly;

The control assembly includes a first circuit board, wherein the first circuit board is arranged in the first accommodating chamber, and is electrically connected to the microphone head; and

The light-emitting assembly includes a light-emitting unit, wherein the light-emitting unit is arranged in the first accommodating chamber and is electrically connected to the first circuit board; and the light-emitting unit is configured to allow emitted light to pass through the outer shell.

In one embodiment, the shell assembly further includes a cover plate and a bottom plate; the cover plate and the bottom plate are respectively arranged at two ends of the outer shell and are enclosed to form the first accommodating chamber; and the cover plate does not have light transmittance.

In one embodiment, the bottom plate does not have light transmittance.

In one embodiment, the shell assembly further includes an inner shell arranged in the first accommodating chamber; the inner shell is provided with a second accommodating chamber; and the first circuit board is arranged in the second accommodating chamber.

2

In one embodiment, the inner shell has light transmittance; the light-emitting unit is arranged in the second accommodating chamber; and the light-emitting unit is configured to allow emitted light to sequentially pass through the inner shell and the outer shell.

In one embodiment, an interval space is provided between the inner shell and the outer shell.

In one embodiment, the light-emitting unit is arranged in the inner shell or the interval space.

10 In one embodiment, the inner shell is a semi-transparent shell.

In one embodiment, the shell assembly further includes a mounting frame and a balancing weight; the mounting frame is arranged in the first accommodating chamber; and the balancing weight and the first circuit board are arranged on two opposite sides of the mounting frame.

In one embodiment, the control assembly further includes an indicator lamp arranged on the shell assembly; the indicator lamp is electrically connected to the first circuit board; and the indicator lamp is configured to directly output emitted light to an outer side of the shell assembly.

In one embodiment, the shell assembly further includes a bottom plate; the bottom plate is arranged at one end of the outer shell; the bottom plate includes a main body portion and a connecting portion; the connecting portion is arranged along a circumferential edge of the main body portion and is connected to the outer shell; the connecting portion is provided with a via hole that penetrates the connecting portion; the indicator lamp is arranged in the via hole; and the indicator lamp is configured to directly output emitted light to an outer side of the connecting portion.

In one embodiment, the shell assembly further includes a light shielding structure; the light shielding structure is annularly arranged at the indicator lamp; and the light shielding structure is configured to output the light emitted by the indicator lamp to outer side of the connecting portion.

In one embodiment, the shell assembly further includes a bottom plate; the bottom plate is arranged at one end of the outer shell; the bottom plate includes a main body portion and a connecting portion; the connecting portion is arranged along a circumferential edge of the main body portion and is connected to the outer shell; the light shielding structure includes a baffle plate and a partition plate; the partition plate is arranged on the main body portion; the baffle plate is connected to the partition plate and resists against the connecting portion; the baffle plate, the partition plate, and the main body portion are enclosed to form a mounting chamber; and the indicator lamp is arranged in the mounting chamber.

50 In one embodiment, the control assembly further includes a function key; the function key is arranged in the outer shell in a penetrating manner and is electrically connected to the first circuit board; the function key is arranged on the outer shell that is on the same side as the indicator lamp; the function key is configured to adjust a signal amplification level input to the microphone and/or a signal strength output by the microphone, and/or to enable or disable a mute function of the microphone.

In one embodiment, the outer shell is a transparent shell.

60 In one embodiment, the light-emitting assembly further includes a connector; the connector is arranged on one side of the first circuit board; and the light-emitting unit is arranged on the connector.

In the microphone product, a shell occupies a large area of the product. According to the microphone provided in the present disclosure, the transparent outer shell is used, and the light-emitting unit is arranged in the first accommodating

chamber, so that light emitted by the light-emitting unit can be transmitted through the outer shell. Therefore, during pickup transmission of the microphone, a user or another person can observe a large-area lighting effect achieved by the microphone, thereby creating a cool lighting atmosphere, achieving an effect of foiling the atmosphere and enhancing the user experience.

In addition, a semi-transparent inner shell can be provided to block internal parts in the microphone, so as to avoid shadows of the internal parts on the outer shell when the light-emitting assembly emits light, making the overall appearance of the product more beautiful and cooler. By the arrangement of an indicator lamp and a related structure, the microphone further creates a cooler lighting atmosphere, without affecting the indication function of the indicator lamp, and the microphone will not interfere with an ambient lamp.

In another aspect, the embodiments further provide a microphone with a unilateral support, including a base, a supporting assembly, a shell assembly, a pickup assembly, and a control assembly. The supporting assembly includes a unilateral support; one end of the unilateral support is connected to the base; the shell assembly includes an outer shell with a first accommodating chamber; the outer shell is configured to be rotatably connected to one end of the unilateral support away from the base; the sound pickup assembly includes a microphone head configured for sound pickup; the microphone head is arranged at the shell assembly; the control assembly includes a first circuit board; the first circuit board is arranged in the first accommodating chamber; and the first circuit board is electrically connected to the microphone head.

In one embodiment, the microphone further includes a shell compensation structure; the shell compensation structure is arranged on the shell assembly; and the shell compensation structure is configured to enhance the strength of the shell assembly.

In one embodiment, the supporting assembly further includes a rotating shaft; the rotating shaft is arranged at one end of the unilateral support away from the base; the outer shell is provided with a mounting hole communicated to the first accommodating chamber; the rotating shaft is arranged in the mounting hole in a penetrating manner; the outer shell is configured to be rotatably connected to the rotating shaft; the shell compensation structure includes a protrusion; and the protrusion is annularly arranged at the mounting hole and is connected to the outer shell.

In one embodiment, the supporting assembly further includes a first gasket with a through hole; the first gasket is arranged between the outer shell and the unilateral support; the rotating shaft is arranged in the through hole in a penetrating manner; the first gasket includes a first portion and a second portion; the second portion is close to one side of the base; and a thickness of the second portion is greater than a thickness of the first portion.

According to the microphone with a unilateral support, the unilateral support is used to support the microphone product, which can further achieve rotation of the microphone and maintain the stability of the microphone, so that the shell of the microphone is designed more simply and beautifully. Furthermore, the strength of the shell assembly is enhanced through the shell compensation structure, which reduces the possibility of breakage of the shell assembly, improves the supporting stability, and prolongs the service life of the product.

BRIEF DESCRIPTION OF THE DRAWINGS

In order to explain the technical solutions of the embodiments of the present disclosure more clearly, the following

will briefly introduce the accompanying drawings used in the embodiments. Apparently, the drawings in the following description are only some embodiments of the present disclosure. Those of ordinary skill in the art can obtain other drawings based on these drawings without creative work.

FIG. 1 is a three-dimensional diagram of a microphone according to an embodiment of this application;

FIG. 2 is a three-dimensional diagram of a microphone in another angle according to an embodiment of this application;

FIG. 3 is a three-dimensional diagram of a microphone in a usage state according to an embodiment of this application;

FIG. 4 is an exploded diagram of a microphone according to an embodiment of this application;

FIG. 5 is an exploded diagram of a microphone in another angle according to an embodiment of this application;

FIG. 6 is an enlarged view of part A of the microphone shown in FIG. 5;

FIG. 7 is a cross-sectional diagram of the microphone shown in FIG. 1 along line VII-VII;

FIG. 8 is a three-dimensional diagram of an outer shell of the microphone shown in FIG. 1;

FIG. 9 is a three-dimensional diagram of an inner shell of the microphone shown in FIG. 1;

FIG. 10 is a cross-sectional diagram of some structures of the microphone shown in FIG. 1 along line X-X;

FIG. 11 is a three-dimensional diagram of then inner shell of the microphone in another shown in FIG. 1;

FIG. 12 is a cross-sectional diagram of an inner shell of the microphone shown in FIG. 7 along line VII-VII;

FIG. 13 is a schematic diagram of a control assembly of the microphone shown in FIG. 1;

FIG. 14 is a schematic diagram of a light-emitting assembly of the microphone shown in FIG. 1;

FIG. 15 is another schematic structural diagram of a light-emitting assembly of a microphone according to an embodiment of this application;

FIG. 16 is still another schematic structural diagram of a light-emitting assembly of a microphone according to an embodiment of this application; and

FIG. 17 is a three-dimensional diagram of a first gasket of the microphone shown in FIG. 1.

DETAILED DESCRIPTION OF THE EMBODIMENTS

In order to facilitate understanding the present disclosure, the present disclosure will be described more comprehensively below with reference to related accompanying drawings. Preferred implementations of the present disclosure are provided in the drawings. However, the present disclosure can be implemented in many different forms, and are not limited to the implementations described herein. On the contrary, these implementations are provided to make the content disclosed in the present disclosure understood more thoroughly and comprehensively.

It should be noted that when an element is referred to as being “fixed to” another element, the element can be directly on another component or there can be a centered element. When an element is considered to be “connected” to another element, the element can be directly connected to another element or there may be a centered element. The terms “inner”, “outer”, “left”, “right”, and similar expressions used herein are for illustrative purposes only and do not necessarily represent the only implementation.

Unless otherwise defined, all technical and scientific terms used herein have the same meaning as those commonly understood by a person skilled in the art to which the present disclosure belongs. Terms used in the specification of the present disclosure herein are merely intended to describe objectives of the specific embodiments, but are not intended to limit the present disclosure. The term "and/or" used herein includes any and all combinations of one or more related listed items.

Referring to FIG. 1, FIG. 2, and FIG. 3, FIG. 1 and FIG. 2 are three-dimensional diagrams of a microphone 100 according to an embodiment of the present disclosure in two different angles. When not in use, the microphone 100 can be rotated to a state shown in FIG. 1 or FIG. 2 for convenient storage and carrying. FIG. 3 is a three-dimensional diagram of a usage state of a microphone 100 according to an embodiment of the present disclosure. When using the microphone 100, a user will rotate and adjust the microphone 100 to a proper angle for better sound pickup, such as a usage state shown in FIG. 3, which is only a schematic diagram of a rotation angle. The microphone 100 disclosed in the present disclosure can be rotated according to a need of the user and maintained in different angles. The present disclosure will not show and elaborate them one by one again.

Referring to FIG. 4 and FIG. 5, the microphone 100 according to an embodiment of the present disclosure includes a shell assembly 1, a sound pickup assembly 2, a control assembly 3, and a light-emitting assembly 4. The shell assembly 1 includes an outer shell 11 with a first accommodating chamber 11d and a mounting seat 12. The mounting seat 12 is connected to the outer shell 11, and the outer shell 11 has light transmittance. The sound pickup assembly 2 includes a microphone head 20 for sound pickup. The microphone head 20 is mounted at the mounting seat 12. The control assembly 3 includes a first circuit board 30. The first circuit board 30 is arranged in the first accommodating chamber 11d and is electrically connected to the microphone head 20. The light-emitting assembly 4 includes a light-emitting unit 40. The light-emitting unit 40 is arranged in the first accommodating chamber 11d and is electrically connected to the first circuit board 30. The light-emitting unit 40 is configured to allow emitted light to pass through the outer shell 11.

In the microphone product, a shell occupies a large area of the product. According to the microphone 100 provided in the present disclosure, the transparent outer shell 11 is used, and the light-emitting unit 40 is arranged in the first accommodating chamber 11d, so that light emitted by the light-emitting unit 40 can be transmitted through the outer shell 11. Therefore, during pickup transmission of the microphone 100, a user or another person can observe a large-area lighting effect achieved by the microphone 100, thereby creating a more intense and cooler lighting atmosphere, achieving an effect of foiling the atmosphere and attracting the attention of people, and enhancing the user experience.

The light-transmittance intensity of the outer shell 11 provided in the embodiments of the present disclosure is flexible. The outer shell may have full light transmittance, or may have high-intensity light transmittance or low-intensity light transmittance. The outer shell 11 can be made of different materials according to an intensity requirement for the light transmittance, so that the shell assembly 1 presents preset light transmittance. The shell assembly 1 may preset the preset light transmittance by coating an outer side wall or an inner side wall of the outer shell 11 or performing surface sanding on the outer shell 11.

The shell assembly 1 may alternatively present the preset light transmittance by embedding a semi-transparent photomask into the outer shell 11. For example, in this embodiment, the shell assembly 1 further includes an inner shell 13 arranged in the first accommodating chamber 11d. The inner shell 13 has light transmittance. Light emitted by the light-emitting unit 40 passes through the inner shell 13 and the outer shell 11 in sequence. Specifically, the outer shell 11 is a transparent shell, and the inner shell 13 is a semi-transparent shell. In this embodiment, to improve the lighting effect displayed by the outer shell 11, the inner shell 13 also has a light filtering property, which can filter out a portion of the light and selectively transmit the emitted light to the outside. Transmitting light waves that a user can accept or like achieves a better result. The semi-transparent shell means that the inner shell 13 allows an amount of light to pass through, but this light is not enough to clearly display objects or details behind.

By the arrangement of the transparent outer shell 11, the light emitted by the light-emitting unit 40 in the microphone 100 can well pass through the transparent outer shell 11 without excessive loss, thereby achieving a better lighting effect. Meanwhile, the semi-transparent inner shell 13 is arranged inside the transparent outer shell 11, so that the light emitted by the light-emitting unit 40 passes through the semi-transparent inner shell 13 and then is transmitted through the transparent outer shell 11, making the light emitted to the outside of the microphone 100 softer. The design of the semi-transparent inner shell 13 can further cover internal components of the microphone 100, such as a circuit boards and wires, playing an aesthetic role. In addition, as the light-emitting unit 40 is arranged in the first accommodating chamber, the brightness of the light near the light-emitting unit 40 is stronger, which makes it easy to see components such as the circuit board and the wires around the light-emitting unit 40. During viewing through the outer shell 11, shadows of the internal components such as the circuit board and the wires will be displayed on the outer shell 11. The arrangement of the semi-transparent inner shell 13 can avoid this situation, so that the overall appearance of the product is more beautiful. Furthermore, the lighting effect of the product is cooler when the light-emitting unit 40 emits light.

Referring to FIG. 4 and FIG. 9, in this embodiment, the inner shell 13 is provided with a second accommodating chamber 13a, and the light-emitting unit 40 is arranged in the second accommodating chamber 13a. The outer shell 11 is made of a transparent material, such as glass, an organic polymer light-transmittance material (an acrylic lamp), a light-transmittance composite material, and light-transmittance plastic as long as the outer shell 11 is transparent. The inner shell 13 is made of a semi-transparent material, such as a thermoplastic polymer, polymethyl methacrylate, polyethylene, polypropylene, polyester, polyvinyl chloride, polyamide, cellulose acetate, polyvinyl chloride, polystyrene, and polytetrafluoroethylene as long as the inner shell 13 is transparent.

Referring to FIG. 4, FIG. 5, and FIG. 8, the outer shell 11 includes a first opening 11a and a second opening 11b which are communicated to the first accommodating chamber 11d and are opposite to each other. The second opening 11b is located at one end of the outer shell 11 away from the mounting seat 12. The shell assembly 1 further includes a cover plate 14 covering the first opening 11a and a bottom plate 15 covering the second opening 11b. The cover plate 14 connects the outer shell 11 to the mounting seat 12, and the outer shell 11 and the mounting seat 12 are arranged on

opposite sides of the cover plate 14. The cover plate 14 does not have light transmittance. The bottom plate 15 does not have light transmittance. In this embodiment, the cover plate 14 and the bottom plate 15 are respectively arranged at two ends of the outer shell 11. The cover plate 14, the bottom plate 15, and the outer shell 11 are enclosed to form the first accommodating chamber 11d. The cover plate 14, the bottom plate 15, and the inner shell 13 are enclosed to form the second accommodating chamber 13a. The second accommodating chamber 13a is located in the first accommodating chamber 11d. An outer diameter of the inner shell 13 is less than an inner diameter of the outer shell 11, and the shape and structure of the inner shell 13 are similar to those of the outer shell 11, and they are barrel-shaped structures with openings in two ends. A spatial distance can be provided between the inner shell 13 and the outer shell 11, or the inner shell and the outer shell resist against each other or in other connection ways. For example, portions of the shells resist against each other, and a partial space is provided. In the embodiments of the present disclosure, a certain spatial distance is provided between the inner shell 13 and the outer shell 11. Specifically, the shells of the inner shell 13 and the outer shell 11 are arranged in parallel, and a side wall of the first accommodating chamber 11d and a side wall of the second accommodating chamber 13a are arranged in parallel, with a distance.

Referring to FIG. 10, in this embodiment, there is an interval space 11f between the outer shell 11 and the inner shell 13. The interval space 11f and the second accommodating chamber 13a are both arranged in the first accommodating chamber 11d. By the arrangement of the interval space 11f, a buffer space can be provided between the two layers of shells, avoiding direct damage to the inner shell 13 after the outer shell 11 is pressed, thereby further protecting the internal components. Meanwhile, the interval space 11f can further provide a buffer space for the light emitted by the light-emitting unit 40 after the light passes through the inner shell 13, and then the light is transmitted out through the outer shell 11, so that the light is displayed more uniformly.

Referring to FIG. 6 and FIG. 7, the shell assembly 1 further includes a mounting frame 16. The mounting frame 16 is arranged in the first accommodating chamber 11d. Specifically, the mounting frame 16 is arranged in the second accommodating chamber 13a. One end resists against the bottom plate 15 and the other end is connected to the mounting seat 12. The first circuit board 30 is arranged in the mounting frame 16. Specifically, in this embodiment, the first circuit board 30 is connected to the mounting frame 16 by screw fixation. In other embodiments, other connection ways can be further used to achieve the connection between the first circuit board 30 and the mounting frame 16. The cover plate 14 covering the first opening 11a, the bottom plate 15 covering the second opening 11b, and the outer shell 11 are enclosed to form the first accommodating chamber 11d, which can protect the component structures located inside the first accommodating chamber 11d and prolong the service life of the product. Meanwhile, the opaque design of the cover plate 14 and the bottom plate 15 ensures that when the light-emitting unit 40 in the microphone 100 emits light, the light can only be transmitted through the outer shell 11. Both the cover plate 14 and the bottom plate 15 are opaque, so that the lighting effect of the product is reflected on the outer shell 11, thereby avoiding the light from irradiating a user or an audience and avoiding interference with the use of the microphone 100. The use experience of the product is better.

Referring to FIG. 4, FIG. 5, and FIG. 6, in this embodiment, the shell assembly 1 further includes a partition plate 17. The partition plate 17 connects the mounting seat 12 with the mounting frame 16, and the mounting seat 12 and the mounting frame 16 are arranged on two opposite sides of the partition plate 17. The partition plate 17 is provided with a hole for a wire to pass through. The wire is configured to electrically connect the microphone head 20 to the first circuit board 30. By the arrangement of the partition plate 17, the positions of the mounting seat 12 and the mounting frame 16 are more obvious and easier to distinguish, so that efficient assembling can be achieved during assembling, and the production efficiency can be improved, thereby reducing the production cost of the product.

The shell assembly 1 further includes a balancing weight 18; the balancing weight 18 is arranged at the mounting frame 16; and the balancing weight 18 and the first circuit board 30 are arranged on the two opposite sides of the mounting frame 16. Specifically, in this embodiment, the balancing weight 18 is fixedly connected to the mounting frame 16 through a screw. In other embodiments, the balancing weight 18 can be connected to the mounting frame 16 through an adhesive, a snap fastener, and the like. The present disclosure does not limit this. The first circuit board 30 is provided with an element and is connected to other parts, so the first circuit board 30 has a weight. When the first circuit board 30 is arranged on a side surface of one side of the mounting frame 16, the center of gravity of the shell assembly is biased towards one side where the first circuit board 30 is located. Therefore, the balancing weight 18 is designed to balance the weight of the first circuit board 30 and other components, thereby ensuring that the center of gravity of the shell assembly 1 is at a preset position and ensuring the self balancing of the product. During use, it is easier for adjustment, thereby enhancing the user experience.

Continuing to refer to FIG. 4, FIG. 5, and FIG. 6, in this embodiment, the shell assembly 1 further includes two decorative sheets 19. The two decorative sheets 19 are respectively arranged on one sides of both the cover plate 14 and the bottom plate 15 away from the outer shell 11. By the arrangement of the decorative sheets 19, exposed portions of the cover plate 14 and the bottom plate 15 can be covered, such as an exposed screw hole or a water mark caused by injection molding, so that the appearance of the product is neater and more beautiful.

In this embodiment, the bottom plate 15 includes a main body portion 151 and a connecting portion 152. The connecting portion 152 is arranged along a circumferential edge 50 of the main body portion 151 and is arranged on one side of the main body portion 151 facing the cover plate 14. The connecting portion 152 is connected to the outer shell 11. An outer surface of the connecting portion 152 and an outer surface of the outer shell 11 resist to form a continuous 55 curved surface or plane, so that surfaces of the shells of the microphone 100 are overall integrated.

Referring to FIG. 5 and FIG. 6, the control assembly 3 further includes an indicator lamp 31. The indicator lamp 31 is arranged in the shell assembly 1 in a penetrating manner. 60 Specifically, the indicator lamp 31 is threaded through the outer shell 11 and is electrically connected to the first circuit board 30. The control assembly 3 further includes a second circuit board 32. The second circuit board 32 is arranged in the first accommodating chamber and is electrically connected to and controls the indicator lamp 31. The second circuit board 32 is electrically connected to the first circuit board 30. By the arrangement of the indicator lamp 31 can

provide an indication function when the control assembly 3 controls the microphone 100, making it easier for a user to observe the adjustment effect more intuitively when adjusting and controlling the microphone 100, and enhancing the user experience. By the arrangement of the second circuit board 32 to control the indicator lamp 31, the indicator lamp 31 can better achieve various indication effects.

Specifically, the connecting portion 152 is provided with a via hole that penetrates through the connecting portion 152, and the indicator lamp 31 is arranged in the via hole. It can be understood that the indicator lamp 31 is arranged in the via hole in a penetrating manner, and a light-emitting side of the indicator lamp 31 faces the outside of the microphone 100 for being observed. There are two or more indicator lamps 31. The number of the via holes is consistent with the indicator lamps 31.

The indicator lamp 31 provided in the embodiments of the present disclosure has flexible and diverse indication modes, which can provide feedback through combinations of different colors or different lighting intensities. The present disclosure does not impose a specific limitation on the indication mode of the indicator lamp 31. In this embodiment, two or more indicator lamps 31 are arranged in a linear direction, and the control assembly 3 controls the microphone. For example, during microphone gain adjustment, the corresponding number of indicator lamps 31 work to emit light, the remaining indicator lamps 31 go out. A user can obtain a control procedure prompt of the control assembly 3 for a microphone gain through the number of the indicator lamps 31 that emit light.

Due to the fact that both the indicator lamp 31 and the light-emitting unit 40 are arranged at the first accommodating chamber 11d, to avoid interference caused by overlapping between the light emitted by the indicator lamp 31 and the light emitted by the light-emitting unit 40, in this embodiment, the shell assembly 1 further includes a light shielding structure. The light shielding structure is annularly arranged on the indicator lamp 31 to output the light emitted by the indicator lamp 31 to an outer side of the shell assembly 1. The light shielding structure can limit the light of the indicator lamp 31 within a range, so that the light can only be transmitted towards the outer side of the shell assembly 1, thereby avoiding the mutual interference and impact between the inside of the shell assembly 1 and the light emitted by the light-emitting assembly 4.

Specifically, the light shielding structure includes a baffle plate 153 and a partition plate 154. The partition plate 154 is arranged on the main body portion 151. There are at least two partition plates 154 which are arranged oppositely. The baffle plate 153 is connected to the partition plates 154 and resists against the connecting portion 152. The baffle plate 153, the partition plates 154, and the main body portion 151 are enclosed to form a mounting chamber. The indicator lamp 31 is arranged in the mounting chamber. In detail, in this embodiment, the second circuit board 32 is arranged opposite to the connecting portion 152. The two partition plates 154 are arranged opposite to each other, and the baffle plate 153 is arranged opposite to the main body portion 151, thereby forming a sealed mounting chamber. The indicator lamp 31 is arranged in the mounting chamber, so that the light emitted by the indicator lamp 31 can be limited in a predetermined direction, thereby controlling an exit direction of the light emitted by the indicator lamp 31 and avoiding the interference between the inside of the shell assembly 1 and the light emitted by the light-emitting assembly 4.

Due to the fact that there are five indicator lamps 31 in the embodiments of the present disclosure, to avoid mutual interference of the light emitted by the various indicator lamps 31, there are six partition plates 154, thereby forming five mounting chambers with the baffle plate 153, the connecting portion 152, and the main body portion 151 respectively to respectively mount the indicator lamps 31, to avoid mutual interference of the light emitted by the five indicator lamps 31. Thus, the indicator lamps 31 emit light according to a preset program to achieve an indicator lamp effect.

In other embodiments, the via hole may not be provided on the connecting portion 152, and only a light transmittance region needs to be arranged at positions of the connecting portion 152 corresponding to the indicator lamps 31. Or, the connecting portion 152 is made of a light transmittance material, and then a non light transmittance region is arranged on the connecting portion 152, leaving only the regions corresponding to the indicator lamps 31 for light transmittance, as long as the light emitted by the indicator lamps 31 can be transmitted out of the connecting portion 152.

The control assembly 3 further includes a function knob 33 and a button 34 configured to control the microphone 100 to be muted. The function knob 33 is arranged in the outer shell 11 in a penetrating manner and is electrically connected to the first circuit board 30. The function knob 33 is configured to adjust the gain effect and/or the volume of the microphone 100. The button 34 is electrically connected to the first circuit board 30. The button 34 is arranged in the outer shell 11 in a penetrating manner and is arranged in parallel with the function knob 33. Specifically, holes for allowing the function knob 33 and the button 34 to be threaded are provided on both the outer shell 11 and the inner shell 13, to facilitate operations of a user. In this embodiment, the button 34 can be pressed to mute the microphone 100 during use, and can be pressed again to relieve the mute effect. The operation is convenient. The function knob 33 has at least two functions. In this embodiment, two functions are taken as an example for introduction. During use, the first function is to adjust the gain effect of the microphone 100 by rotation, and the second function is to adjust the volume of earphones by rotation. The two functions can be switched by pressing the function knob 33. In other embodiments, the function knob 33 may alternatively have a third function or more functions. The functions can be switched by pressing. The function knob integrates multiple function adjustments, so that the overall operation buttons of the product are reduced, and the appearance is neater and more beautiful.

Referring to FIG. 13, the control assembly 3 further includes a first audio jack 35 arranged in the shell assembly 1 in a penetrating manner and connected to an external audio device, an earphone jack 36 for being connected to external earphones, and a second audio jack 37 for being connected to an external device to transmit data. The first audio jack 35, the earphone jack 36, and the second audio jack 37 are all electrically connected to the first circuit board 30. Specifically, the first audio jack 35, the earphone jack 36, and the second audio jack 37 are all arranged in the bottom plate 15 in a penetrating manner. The bottom plate 15 is provided with corresponding holes. The first audio jack 35 is configured to be connected to another external device such as a sound card or an audio device, to achieve seamless compatibility. The second audio jack 37 is configured to be connected to another device, such as a computer and a tablet, to achieve data transmission such as audio data transmis-

sion. The two audio jacks enhance the functionality of the microphone 100, which is convenient for a user to use multiple interfaces. The main function of the earphone jack 36 is to be connected to the earphones for transmission of audio signals, thus allowing a user to listen to sound through the earphones. Specifically, the second audio jack 37 can be a USB interface or a type-c interface.

Referring to FIG. 4 to FIG. 6 and FIG. 14, in this embodiment, the light-emitting assembly 4 further includes a third circuit board 41 arranged in the first accommodating chamber 11d. Specifically, the third circuit board 41 is arranged in the second accommodating chamber 13a. The third circuit board 41 is electrically connected to and controls the light-emitting unit 40 to emit light. The third circuit board 41 is electrically connected to the first circuit board 30. There are two or more third circuit boards 41, and there are two or more light-emitting units 40. The light-emitting units 40 are arranged on the third circuit boards 41, and the third circuit boards 41 are annularly arranged on an outer side of the first circuit board 30. The third circuit boards 41 can be flexible circuit boards or rigid circuit boards. The present disclosure does not limit this. The light-emitting units 40 are LEDs. The LEDs can emit light with various colors and can be selected according to a need. The third circuit boards 41 are electrically connected to the light-emitting units 40, which can better control the light emission of the light-emitting units 40 to achieve various lighting effects, so that the user experience is better. By the arrangement of the plurality of third circuit boards 41 and light-emitting units 40, the light can be displayed more uniformly on the outer shell 11, thereby enhancing the lighting effect of the microphone 100, enhancing the user experience, and improving the competitiveness of the product.

Further, the light-emitting assembly 4 further includes a connector 42; the connector 42 is arranged on one side of the first circuit board 30; and the light-emitting unit 40 is arranged on the connector 42. Specifically, in this embodiment, the third circuit board 41 is arranged on the connector 42. The connector 42 is connected to the mounting frame 16 and resists against the first circuit board 30. A connection relationship between the connector 42 and the mounting frame 16 is buckle connection. One of the connector 42 and the mounting frame 16 is provided with a buckle, and the other one is provided with a buckle slot, to achieve snap fit. In other embodiments, the connection relationship between the connector 42 and the mounting frame 16 may alternatively be fixed connection. Namely, the connection is achieved through a screw or an adhesive. The present disclosure does not impose a specific limitation on this.

Specifically, in the embodiments of the present disclosure, the connector 42 includes a connecting plate 421, a first extension plate 422 arranged on one side of the connecting plate 421, and a second extension plate 423 arranged on the other side of the connecting plate 421. The first extension plate 422 and the second extension plate 423 are respectively connected to two opposite sides of the connecting plate 421 and have an angle with the connecting plate 421. The first extension plate, the second extension plate, and the connecting plate are enclosed to form a semi-enclosed groove-like structure. The connecting plate 421 is in buckle connection with the mounting frame 16. One of the connecting plate and the mounting frame is provided with a buckle, and the other one is provided with a buckle slot, to achieve snap fit. The third circuit board 41 is arranged on the first extension plate 422 or the second extension plate 423. When there are a plurality of third circuit boards 41, the third circuit boards 41 are arranged on both the first extension

plate 422 and the second extension plate 423. Specifically, in the embodiments of the present disclosure, the third circuit boards 41 are arranged on both the first extension plate 422 and the second extension plate 423.

In this embodiment, there are two connectors 42 which are arranged on two opposite sides of the first circuit board 30, and the connectors 42 wrap around at least a portion of the first circuit board 30. The two connectors 42 are respectively connected to two opposite sides of the mounting frame 16. The first circuit board 30 and the balancing weight 18 are respectively arranged on two other opposite sides of the mounting frame 16. The two connectors 42, the first circuit board 30, and the balancing weight 18 are annularly arranged at a periphery of the mounting frame 16. The two connectors 42 wrap around at least a portion of the first circuit board 30 and at least a portion of the balancing weight 18, and respectively resist against the first circuit board 30 and the balancing weight 18. Namely, the mounting frame 16, the first circuit board 30, and the balancing weight 18 are partially or entirely arranged between the two connectors 42, and the semi-enclosed groove-like structures of the two connectors 42 accommodate the mounting frame, the first circuit board, and the balancing weight. Specifically, the connecting plate 421 is connected to the mounting frame 16 and resists against the first circuit board 30 and the balancing weight 18. The first circuit board 30 and the balancing weight 18 are sandwiched between the first extension plate 422 and the second extension plate 423.

Specifically, the entire mounting frame 16 is generally a rectangular structure with a thickness, which has four side surfaces distributed in four vertical directions, namely a first side surface 161, a second side surface 162, a third side surface 163, and a fourth side surface 164. The first side surface 161 and the third side surface 163 are two side surfaces with large widths, and the second side surface 162 and the fourth side surface 164 are two side surfaces with small widths. The first side surface 161 and the third side surface 163 are arranged opposite to each other, and the second side surface 162 and the fourth side surface 164 are arranged opposite to each other. The first circuit board 30 and the balancing weight 18 are respectively arranged on the first side surface 161 and the third side surface 163. The two connectors 42 are respectively arranged on the second side surface 162 and the fourth side surface 164. By the arrangement of the connectors 42, the light-emitting units 40 can be better fixed, and detachment of the light-emitting units 40 can be avoided. Meanwhile, the two opposite connectors 42 wrap around the first circuit board 30, which can better protect the first circuit board 30 and make a better use of an internal space of the product, thereby reducing the cost of the product. The light-emitting units 40 are arranged on the two opposite sides of the first circuit board 30. This design can make the distribution of light sources more uniform.

Specifically, the light-emitting assembly 4 further includes an on/off button 43 arranged in the shell assembly 1 in a penetrating manner. The on/off button 43 is electrically connected to the third circuit board 41 to control the light-emitting unit 40. The on/off button 43 is configured to control the light-emitting unit 40 to be turned on and turned off, and to adjust the color and flashing mode of the light source, so that the product has high functionality.

Referring to FIG. 15, FIG. 15 is another schematic structural diagram of a light-emitting assembly of a microphone according to an embodiment of this application. In this embodiment, only a portion of the structure and positional relationship when the light-emitting assembly 4' is compared with the light-emitting assembly 4 in the previous

embodiment. In this embodiment, the light-emitting assembly 4' includes a light-emitting unit 40' and a third circuit board 41'. The light-emitting unit 40' is arranged on the third circuit board 41', and the third circuit board 41' is arranged at the inner shell 13. Specifically, the third circuit board 41' is arranged on an inner wall of the inner shell 13. The inner shell 13 is provided with a penetrating hole. The light-emitting unit 40' is arranged in the hole in a penetrating manner. A light-emitting surface of the light-emitting unit 40' faces the outer shell 11. When the light-emitting unit 40' is turned on, emitted light can be transmitted through the outer shell 11. In this embodiment, the third circuit board 41' is arranged in an axial direction of the inner shell 13. In other embodiments, the third circuit board 41' may alternatively be arranged in a circumferential direction of the inner shell 13.

Referring to FIG. 16, FIG. 16 provides still another schematic structural diagram of a light-emitting assembly of a microphone. In this embodiment, when the light-emitting assembly 4" is compared with the light-emitting assembly 4 in the previous embodiment, only the positional relationship changes. Specifically, the light-emitting assembly 4" includes a light-emitting unit 40" and a third circuit board 41". The light-emitting unit 40" is arranged on the third circuit board 41", and the third circuit board 41" and the light-emitting unit 40" are arranged in the interval space 11f. Specifically, the third circuit board 41' is arranged on an outer side wall of the inner shell 13. A light-emitting surface of the light-emitting unit 40" faces the outer shell 11. When the light-emitting unit 40" is turned on, emitted light can be transmitted through the outer shell 11. In this embodiment, the third circuit board 41" is arranged in an axial direction of the inner shell 13. In other embodiments, the third circuit board 41" may alternatively be arranged in a circumferential direction of the inner shell 13.

Continuing to refer to FIG. 1 to FIG. 7, the microphone 100 further includes a base 5 and a supporting assembly 6. The supporting assembly 6 is connected to the base 5, and the supporting assembly 6 is configured to be rotatably connected to the shell assembly 1. The supporting assembly 6 includes a support 61 and a rotating shaft 62. One end of the support 61 is connected to the base 5, and the rotating shaft 62 is arranged at one end of the support 61 away from the base 5. The rotating shaft 62 is arranged in the outer shell 11 in a penetrating manner, and the outer shell 11 is configured to rotate around the rotating shaft 62.

In this embodiment, the support 61 is a unilateral support, and shell assembly 1 is supported and rotated only through the unilateral support. Specifically, the support 61 is only connected to one side surface of the outer shell 11. In this way, most of the area of the outer shell 11 can be redesigned for layout, so that the appearance of the product is neater and more beautiful. When the light-emitting unit 40 emits light, the outer shell 11 can show a larger area of light and a cooler lighting effect.

Referring to FIG. 7, in this embodiment, the support 61 is connected to the base 5 by screwing. Specifically, an internal threaded hole is provided at one end of the support 61 connected to the base 5, and a bolt is in threaded connection with the internal threaded hole of the support 61 through the base 5. In this embodiment, the base 5 can be removed from the support 61 through the bolt, so that the microphone 100 can be connected to an external cantilever support through the internal threaded hole on the support 61, thereby expanding the usage scenario of the microphone 100. The microphone 100 can not only be used on a surface of an object, such as a desktop, but also suspended and used through the

external cantilever support. By the arrangement of the base 5, the microphone 100 can be placed steadily on the surface of the object. The shell assembly 1 can rotate relative to the rotating shaft 62. As the shell assembly 1 can rotate, it is convenient for a user to adjust an inclination angle of the microphone 100, and it is more convenient for use and for the microphone head 20 to pick up sounds. The user experience is enhanced.

Referring to FIG. 4 and FIG. 5, the supporting assembly 6 further includes a first gasket 63 with a through hole 63a. The first gasket 63 is arranged between the outer shell 11 and the support 61. The rotating shaft 62 is arranged in the through hole 63a in a penetrating manner. Referring to FIG. 17 for details, the first gasket 63 includes a first portion 631 and a second portion 632. The first portion 631 and the second portion 632 are located on two opposite sides of an axis of the through hole 63a, and a thickness of the second portion 632 is greater than a thickness of the first portion 631. The second portion 632 is located at one end of the first gasket 63 close to the base 5. In this embodiment, the first gasket 63 is made of a soft material such as silica gel and rubber. The first gasket 63 can enlarge a contact area between the outer shell 11 and the support 61, so that the shell assembly 1 can be maintained in a desired angle after rotating relative to the support 61 to adjust the inclination angle. The first gasket 63 is set to have a thin top and a thick bottom, so that the shell assembly 1 can play a role of supporting and compensation under the action of its gravity and a supporting force of the rotating shaft 62. The second portion is thick, which can better support the shell assembly 1.

Referring to FIG. 8, the outer shell 11 is provided with a first mounting hole 11c and a first protrusion 111 configured to enhance the strength of the outer shell 11. The first protrusion 111 is annularly arranged at the first mounting hole 11c. The rotating shaft 62 is arranged in the first mounting hole 11c in a penetrating manner, and at least a portion of the first gasket 63 is arranged in the first mounting hole 11c in a penetrating manner.

Referring to FIG. 9, in this embodiment, a second mounting hole 13b for threading the rotating shaft 62 is also correspondingly provided at a position, corresponding to the first mounting hole 11c of the outer shell 11, on the inner shell 13. An inner diameter of the second mounting hole 13b is approximately equal to an inner diameter of the first mounting hole 11c. A second protrusion 131 is arranged at a periphery of the second mounting hole 13b to enhance the strength of the inner shell 13. The outer shell 11 has light transmittance, achieving light transmittance. Meanwhile, if the first mounting hole 11c is provided on the outer shell 11, the strength of the outer shell 11 will be inevitably affected. As the first protrusion 111 is arranged at the periphery of the first mounting hole 11c, it plays a reinforcing bar role, so that the strength of the outer shell 11 can be enhanced, avoiding damage to the outer shell 11 and ensuring that the product has good quality. Furthermore, the first protrusion 111 protrudes out of the outer shell 11, so that a gap is reserved between the support 61 and the outer shell 11. This allows the microphone 100 to have an avoidance space when it is rotated or deflects due to an external force, thereby avoiding friction and collision between the outer shell 11 and the support 61, avoiding the damage to the outer shell 11, and ensuring the beautiful appearance of the microphone 100.

Specifically, a third protrusion 132 is further arranged on the inner shell 13. The third protrusion 132 is annularly arranged at a periphery of the second protrusion 131 and is connected to the inner shell 13. A height of the third

15

protrusion 132 is greater than that of the second protrusion 131. In this embodiment, the third protrusion 132 is integrally connected to the second protrusion 131. By the additional arrangement of the third protrusion 132, the shell strength close to the second mounting hole 13b of the inner shell 13 is further enhanced, ensuring that the shell strength of the inner shell 13 can be enough to bear and support the microphone 100. During rotation relative to the rotating shaft 62, it can still ensure that the shell strength will not be lowered, thereby prolonging the service life of the product.

Referring to FIG. 11 and FIG. 12, the inner shell 13 is further provided with a fourth protrusion 133. The fourth protrusion 133 is annularly arranged at the second mounting hole 13b. The fourth protrusion 133 is arranged on one side of the inner shell 13 away from the outer shell 11. In this embodiment, the fourth protrusion 133 and the second protrusion 131, as well as the third protrusion 132, are respectively arranged on two sides of the inner shell 13, and are annularly arranged at the second mounting hole 13b. By the arrangement of the fourth protrusion 133, the shell strength of the inner shell 13 close to the second mounting hole 13b is further enhanced, thereby reducing the impact of the second mounting hole 13b on the shell strength of the inner shell 13.

Specifically, continuing to refer to FIG. 17, the first gasket 63 is provided with a positioning column 633. The positioning column 633 is located on the first portion 631 and faces one side of the outer shell 11. A positioning hole 11e is provided at a corresponding position on the outer shell 11. The positioning column 633 is arranged in the positioning hole 11e in a penetrating manner. In this embodiment, the positioning column 633 is made of a soft material and resists against the inner shell 13, specifically, the second protrusion 131. In other embodiments, the positioning column 633 is arranged in the positioning hole 11e in the penetrating manner and may not resist against the inner shell 13 or the second protrusion 131. By the arrangement of the positioning column 633 on the first gasket 63 and cooperation with the positioning hole 11e on the outer shell 11, it can ensure that the relative positions of the first gasket 63 and the outer shell 11 are fixed, so that when the outer shell 11 rotates relative to the rotating shaft 62, the first gasket 63 rotates with the outer shell 11, thereby increasing the friction force during the rotation, ensuring that the shell assembly 1 can be maintained in an angle desired by a user without rotation, and improving the stability of the microphone 100. Referring to FIG. 4 and FIG. 5, the supporting assembly 6 further includes a fastener 64. The fastener 64 is connected to one end of the rotating shaft 62 away from the outer shell 11 and is located on one side of the support 61 away from the outer shell 11. In this embodiment, the rotating shaft 62 is connected to the fastener 64 in a non-rotatable manner. The end of the rotating shaft 62 connected to the fastener 64 is designed as a polygon along an axial view. A matching slot is provided in the fastener 64, so that the non-rotatable connection between the rotating shaft 62 and the fastener 64 is achieved. In other embodiments, the rotating shaft 62 can be fixedly connected to or integrally formed with the corresponding fastener 64. The supporting assembly 6 further includes a second gasket 65. The second gasket 65 is arranged between the support 61 and the fastener 64. By the arrangement of the fastener 64, the rotating shaft 62 passes through the support 61 to ensure the length of the rotating shaft 62 and to further play a balancing role. The support 61 acts as a fulcrum, so that the shell assembly 1 and the fastener 64 are located at two ends of the rotating shaft 62, thereby balancing the weight of the shell assembly 1. In

16

addition, the fastener 64 can further ensure that the rotating shaft 62 will not fall off from the support 61. The second gasket 65 can enlarge a contact area between the support 61 and the fastener 64, thereby achieving antislip and stabilizing effects.

The sound pickup assembly 2 further includes a mesh enclosure 21, and the mesh enclosure 21 covers the microphone head 20. In this embodiment, the mesh enclosure 21 further covers the mounting seat 12 and resists against the cover plate 14. The shell assembly 1 further includes a sponge cover 1A. The sponge cover 1A is covered at the mesh enclosure 21 and resists against the outer shell 11. On the one hand, the sponge cover 1A can effectively prevent popping noise, protect the microphone head 20 of the microphone 100, and prevent saliva splashing. On the other hand, an air flow of plosive directly blown to the microphone head 20 can be reduced, thereby prolonging the service life of the microphone 100 and enhancing the user experience.

The various technical features in the foregoing embodiments may be randomly combined. For concise description, not all possible combinations of the various technical features in the above embodiments are described. However, provided that combinations of these technical features do not conflict with each other, the combinations of the various technical features are considered as falling within the scope of this specification. The foregoing embodiments merely express several implementations of the present disclosure. The descriptions thereof are relatively specific and detailed, but are not understood as limitations on the scope of the present disclosure. A person of ordinary skill in the art can also make several transformations and improvements without departing from the idea of this application. These transformations and improvements fall within the protection scope of this application. Therefore, the protection scope of the patent of this application shall be subject to the appended claims.

What is claimed is:

1. A microphone, comprising:
a shell assembly, comprising an outer shell with a first accommodating chamber, wherein the outer shell has light transmittance;
a sound pickup assembly, comprising a microphone head for sound pickup, wherein the microphone head is arranged in the shell assembly;
a control assembly, comprising a first circuit board, wherein the first circuit board is arranged in the first accommodating chamber, and is electrically connected to the microphone head; and
a light-emitting assembly, comprising a light-emitting unit, wherein the light-emitting unit is arranged in the first accommodating chamber and is electrically connected to the first circuit board; and the light-emitting unit is configured to allow emitted light to pass through the outer shell.

2. The microphone according to claim 1, wherein the shell assembly further comprises a cover plate and a bottom plate; the cover plate and the bottom plate are respectively arranged at two ends of the outer shell and are enclosed to form the first accommodating chamber; and the cover plate is impervious to light.

3. The microphone according to claim 2, wherein the bottom plate is impervious to light, and the outer shell is a transparent shell.

4. The microphone according to claim 1, wherein the shell assembly further comprises a mounting frame and a balancing weight; the mounting frame is arranged in the first

accommodating chamber and configured to support the balancing weight and the first circuit board; and the balancing weight and the first circuit board are installed on the mounting frame and located two opposite sides of the mounting frame.

5. The microphone according to claim 1, wherein the control assembly further comprises at least one indicator lamp arranged on the shell assembly; the indicator lamp is electrically connected to the first circuit board, the shell assembly further comprises a bottom plate; the bottom plate is arranged at one end of the outer shell; the bottom plate comprises a main body portion and a connecting portion; the connecting portion is arranged along a circumferential edge of the main body portion and is connected to a bottom end surface of the outer shell; the connecting portion is provided with at least one via hole that penetrates the connecting portion; the indicator lamp is arranged in the at least one via hole; and the at least one indicator lamp is configured to directly output emitted light to an outer side of the connecting portion via the at least one via hole.

6. The microphone according to claim 5, wherein the at least one indicator lamp comprises a plurality of indicator lamps, the at least one via hole comprises a plurality of via holes, the shell assembly further comprises a light shielding structure; the light shielding structure has a plurality of mounting chambers, each of the mounting chambers is disposed adjacent one corresponding via hole of the via holes and is annularly arranged at one corresponding indicator lamp of the indicator lamps.

7. The microphone according to claim 6, wherein the shell assembly further comprises a bottom plate; the bottom plate is arranged at one end of the outer shell; the bottom plate comprises a main body portion and a connecting portion; the connecting portion is arranged along a circumferential edge of the main body portion and is connected to the outer shell; the light shielding structure comprises a baffle plate and a partition plate; the partition plate is arranged on the main body portion; the baffle plate is connected to the partition plate and resists against the connecting portion; the baffle plate, the partition plate, and the main body portion are enclosed to form a plurality of mounting chambers; and the indicator lamp is arranged in the mounting chamber.

8. The microphone according to claim 1, wherein the control assembly further comprises a function key; the function key is arranged in the outer shell in a penetrating manner and is electrically connected to the first circuit board; the function key is arranged on a through hole disposed at middle of the outer shell adjacent to the indicator lamp; the function key is configured to adjust a signal amplification level input to the microphone and/or a signal strength output by the microphone, and/or to enable or disable a mute function of the microphone.

9. The microphone according to claim 1, wherein the light-emitting assembly comprises a plurality of light-emitting units, the light-emitting units are arranged in the first accommodating chamber and are electrically connected to the first circuit board; and the light-emitting units are arranged along a longitudinal direction of the first accommodating chamber and are configured to allow emitted light to pass through the outer shell.

10. The microphone according to claim 9, wherein each of the light-emitting units comprises a plurality of emitting elements arranged along the longitudinal direction of the first accommodating chamber.

11. The microphone according to claim 9, wherein the light-emitting assembly further comprises a connector; and the light-emitting units are arranged on different sides of the connector respectively.

5. 12. The microphone according to claim 9, wherein the connector includes a connecting plate, a first extension plate connected one side of the connecting plate, and a second extension plate connected the other side of the connecting plate, two light-emitting units of the light-emitting units are mounted on the first extension plate and the second extension plate respectively.

13. A microphone, comprising:

a shell assembly, comprising an outer shell with a first accommodating chamber, wherein the outer shell has light transmittance;

a sound pickup assembly, comprising a microphone head for sound pickup;

a control assembly, comprising a first circuit board, wherein the first circuit board is arranged in the first accommodating chamber, and is electrically connected to the microphone head; and

a light-emitting assembly, comprising a light-emitting unit, wherein the light-emitting unit is arranged in the first accommodating chamber and is electrically connected to the first circuit board; and the light-emitting unit is configured to allow emitted light to pass through the outer shell,

wherein the shell assembly further comprises an inner shell arranged in the first accommodating chamber, the inner shell is provided with a second accommodating chamber; and the first circuit board is arranged in the second accommodating chamber.

14. The microphone according to claim 13, wherein the inner shell has light transmittance; the light-emitting unit is arranged in the second accommodating chamber; and the light-emitting unit is configured to allow emitted light to sequentially pass through the inner shell and the outer shell.

15. The microphone according to claim 13, wherein an interval space is provided between the inner shell and the outer shell, and the light-emitting unit is arranged in the inner shell or the interval space.

16. The microphone according to claim 13, wherein the inner shell is a semi-transparent shell.

17. A microphone, comprising:

a shell assembly comprising an outer shell with a first accommodating chamber;

a sound pickup assembly, comprising a microphone head for sound pickup; and

a control assembly, comprising a first circuit board, wherein the first circuit board is arranged in the first accommodating chamber, and is electrically connected to the microphone head;

wherein the microphone further comprises a base and a supporting assembly; the supporting assembly comprises a unilateral support; one end of the unilateral support is connected to the base, and the unilateral support first extends upwards in a first direction perpendicular to the base, and then extends upwards in a second direction inclined to the first direction, and finally extends upwards in a third direction substantially parallel to the first direction to form the other one end of the unilateral support; and the outer shell is configured to be rotatably connected to the other end of the unilateral support away from the base.

18. The microphone according to claim 17, wherein the microphone further comprises a shell compensation structure; the shell compensation structure is arranged on the

19

shell assembly; and the shell compensation structure is configured to enhance the strength of the shell assembly.

19. The microphone according to claim **18**, wherein the supporting assembly further comprises a rotating shaft; the rotating shaft is arranged at one end of the unilateral support away from the base; the outer shell is provided with a mounting hole communicated to the first accommodating chamber; the rotating shaft is arranged in the mounting hole in a penetrating manner; the outer shell is configured to be rotatably connected to the rotating shaft; the shell compensation structure comprises a protrusion; and the protrusion is annularly arranged at the mounting hole and is connected to the outer shell. 5

20. The microphone according to claim **19**, wherein the supporting assembly further comprises a first gasket with a through hole; the first gasket is arranged between the outer shell and the unilateral support; the rotating shaft is arranged in the through hole in a penetrating manner; the first gasket comprises a first portion and a second portion; the second portion is close to one side of the base; and a thickness of the second portion is greater than a thickness of the first portion. 10 15 20
